ASSEMBLING MACHINE

Carl Habel, Warren, Ohio, assignor to General
Motors Corporation, Detroit, Mich., a corpora-
tion of Delaware

Application March 31, 1950, Serial No. 153,070

6 Claims. (Cl. 29—203)

1

This invention relates to lamp sockets and terminal assemblies and its object is to provide a machine for facilitating the assembly of a lamp socket, a wire providing a terminal contact for engagement with a contact of the lamp base received by the socket, a spring which urges the terminal contact into engagement with the lamp base contact and a bushing for insulating the spring from the terminal contact.

Further objects and advantages of the present invention will be apparent from the following description, reference being had to the accompanying drawings, wherein a preferred embodiment of the present invention is clearly shown.

In the drawings:

Fig. 1 is a plan view of the machine.

Figs. 2 and 3 together provide a side view partly in section on line 2—2 of Fig. 1.

Fig. 4 is a fragmentary view in the opposite direction of arrow 4 of Fig. 3.

Fig. 5 is a view in the direction of arrow 5 of Fig. 1 and shows a hopper feed for the lamp sockets.

Fig. 6 is a sectional view on line 6—6 of Fig. 5 and is drawn to a larger scale.

Fig. 7 is a plan view of a part 130 of the hopper feed shown in Figs. 1 and 5.

Fig. 8 is a view of part 130 in the direction of arrow 8 of Fig. 7.

Figs. 9 and 10 are plan and side views, respectively, of a part 135 of the socket hopper feed shown in Figs. 1 and 5.

Figs. 11 and 12 are plan and edge views, respectively, of a part 137 of the socket hopper feed shown in Figs. 1 and 5.

Figs. 13 and 14 are plan and edge views, respectively, of the part 136 of the socket hopper feed shown in Fig. 1.

Figs. 15 and 16 are plan and edge views, respectively, of a part 138 of the socket hopper feed shown in Figs. 1 and 5.

Figs. 17, 18, 19 and 20 show sectional views of the parts in various stages of assembly upon a workholder provided by a dial 100.

Fig. 21 shows a side view of the completed assembly, the arrows *a* indicating the manner in which the completed assembly is rejected from a supporting dial 100.

Fig. 22 is an enlargement of the portion of the sectional view shown in the upper left part of Fig. 2.

Fig. 23 is a view similar to Fig. 2 and shows different positions of certain parts shown in Fig. 22.

2

Fig. 24 is a view of a part 195 in the direction of arrow 24 of Fig. 22.

Fig. 25 is a fragmentary, sectional view on line 25—25 of Fig. 22.

Fig. 26 is a sectional view on line 26—26 of Fig. 22.

Fig. 27 is a sectional view on line 27 of Fig. 2.

Fig. 28 is an enlarged sectional view on line 28—28 of Fig. 1.

Fig. 29 is a view in the direction of arrow 29 of Fig. 28.

Figs. 30 and 31 are enlarged fragmentary, sectional views taken, respectively, on line 30—30 of Fig. 28 and line 31—31 of Fig. 29.

Fig. 32 is a fragmentary view in the direction of arrow 32 of Fig. 1.

Fig. 33 is an enlarged edge view of one of the workholders.

Fig. 34 is an enlarged plan view on line 34—34 of Fig. 33, the plate 104 being partly broken away.

Fig. 35 is a sectional view on line 35—35 of Fig. 34.

Figs. 36, 37 and 38 are fragmentary, sectional views on an enlarged scale taken, respectively, on lines 36—36, 37—37 and 38—38 of Fig. 1.

Referring to Figs. 1 and 2, a plate 40 is supported above the floor by a boxlike frame having horizontal members 41 supported by vertical members 42 attached at their lower ends to a structure 43 which rests on the floor. Plate 40

supports a plate 44 to which tubes 45 and 46 are welded and a plate 47 to which a tube 48 is welded. Tubes 45, 46 and 48 support, respectively, bearings 49, 50 and 51 for shafts 52, 53 and 54, respectively. Shaft 54 supports bearings 55 and 56 for a shaft 57. Referring to Fig. 28, plate 40 supports a plate 60 to which a tube 61 is welded. Tube 61 supports bearings 62 for a shaft 63.

Plate 40 (Fig. 32) supports a plate 64 which is welded to a tube 65 which supports bearings 66 for a shaft 67 connected with a sprocket 68 connected by chain 69 with a sprocket 70 (Fig. 2) attached to shaft 57. Shaft 57 is connected with a sprocket 71 connected by a chain 72 with a sprocket 73 attached to shaft 52. A sprocket 74 attached to shaft 52 is connected by a chain 75 with a sprocket 76 (Fig. 28) attached to shaft 63.

Shaft 52 (Fig. 2) is connected with a gear 80 which meshes with a gear 81 connected with shaft 53. Shaft 53 (Fig. 27) has an arm 82 carrying a stud 83 providing a pivot for a roller 84 adapted to be received successively by notches 85 of a Geneva gear disc 86 attached to shaft 54. Shaft 53 provides a cylindrical surface 87 for successive engagement with cylindrical surfaces

50
55

88 of notches provided for in plate 86. When motion is not being transmitted to disc 86 by the roller 84, a surface 88 is engaged by the surface 87 to prevent rotation of shaft 54.

Shaft 52 is connected by a coupling 90 with a shaft 91 of a speed reducer in a housing 92. The input shaft 93 of the speed reducer is connected by groove pulley 94, belt 95 and a grooved pulley 96 with the shaft 97 of an electric motor 98.

Shaft 54 supports and drives a dial 100 which constitutes a rotary conveyor and is attached to a ring 101 which is welded to shaft 54. Referring to Fig. 1, dial 100 is provided with equi-angularly spaced notches 102 and recess 103. Referring to Figs. 33, 34 and 35, each recess 103 receives a plate 104 retained by screws 105. Plate 104 provides a recess 106 which receives work-retaining levers 107 pivoted on pins 108 attached to the dial 100. A helical spring 109 has its turns received in a recess provided by plate 104 around a stud 110 attached to dial 100. Spring 109 is retained by plate 104 and the ends 111 of the spring press against the levers 107 so as to urge the one which is upper in Fig. 34 clockwise and the one which is lower, counterclockwise, these movements of the levers being stopped by engagement of the levers with surfaces 112 provided by plate 104. The wider portion of each notch 102 receives a lamp socket LS as shown in Fig. 17. The socket is moved sidewise in between the levers 107 by a feeding device to be described. As the lamp socket LS moves into the notch 102, it engages levers 107 and cams them apart. When the lamp socket LS has been pushed as far as it will go into the notch, the levers 107 are caused by the spring 109 to retain the lamp socket upon the dial.

The lamp sockets LS are contained in a hopper feed device 120 (Figs. 1 and 5) which is operated by an electric motor 121. This hopper feed is the one which is available on the market and it causes the lamp sockets to be discharged by the hopper into a chute 122 shown in large scale in Fig. 6. This chute 122 comprises bars 123 connected by plate 124 and having grooves 125 for receiving the flanges f for the lamp sockets. Flanges f are retained by plates 126 of the chute. The chute 122 directs the lamp socket into a member 130 (Figs. 7 and 8) which serves as a chute extension; and it is supported above the plate 40 by a bracket 131. Member 130 provides a groove 132 into which the lamp sockets LS descend from the chute 122 as indicated in Fig. 7. As the lamp sockets descend into this groove, their flanges f engage upon groove surfaces 133 and 134 provided, respectively, by plates 135 (Fig. 9) and 136 (Fig. 13). These groove surfaces 133 and 134 are continuations of the grooves 125 (Fig. 6) of bars 123. The flanges f of the lamp sockets are retained upon the surfaces 133 and 134 by plate 137 (Fig. 11) and plate 138 (Fig. 15), said plates being extensions of plates 126 in Fig. 6.

The lowermost lamp socket LS received by member 130 stops on a surface 132a of the groove 132 which, as shown in Fig. 7, extends obliquely and then vertically seen in this view. The outlet 132b of groove 132 will be in close proximity to a notch 102 of the dial 100 after the dial has been indexed as shown in Fig. 1. The lamp socket nearest the dial at the exit 132b of the groove 132 is moved from member 130 into the work-holder by a bar 140 which is shown in Fig. 32 in the position for completing movement of a lamp socket into the notch of the dial. The bracket 131 supports a rod 141 providing a pivot for a

lever 142 carrying a roller 143 which follows a cam 144 driven by shaft 67, that roller being urged against the cam by a spring 145 connected with the lever 142 and the bracket 131. A rod 141 provides a pivot for a lever 146 which a spring 147 connecting levers 142 and 146, and operating to urge lever 146 counterclockwise against a stop disc 148 having an eccentric shank 149 extending within the lever 142. This shank 149 receives a screw (not shown) which, after the shank 149 has been turned to adjust the position of disc 148, is tightened. Lever 146 has a notch 150 for receiving a pin or roller 151 attached to bar 140. Movement of lever 142 counterclockwise is transmitted by spring 147 to lever 146 to cause the bar 140 to push the lamp socket LS into a notch 102 of dial 100.

As shown in Fig. 18, the next operation of the machine is to assemble with the lamp socket a spring s. The springs s are contained in a feeder 160 (Fig. 3) known as a vibrating bowl feeder, there being an electrically operated device which vibrates it. Feeder 160 is mounted upon horizontal angle bars 161 (Figs. 1 and 2) which are supported above the plate 40 by vertical angle bars 162. The bars 161 and 162 tend to absorb the vibrations of the feeder. The function of the device 160 is to cause the springs to jiggle endwise into a tube 164 through which they gravitate to the lower end of tube 164 shown in Figs. 28 and 29. These springs are successively received in a bore 165 of a block 166 attached to a plate 167 attached to a pad 168 welded to tube 61. The lowermost spring s is received upon a gate plate 169 having an opening 169a for admission of the spring when released by left movement of plate 169. Plate 169 is attached to a bar 170 carrying a roller 171 received by a cam race 172 of a cam 173 driven by shaft 63. When cam 173 moves bar 170 left (Figs. 30 and 31), it forces a spring 174 left to effect left movement of a rod 175 carrying a fiber bar 176 so that the next to the lowest spring s will be pressed by spring 174 against the side of the bore 165 of block 166. Therefore, at the time plate 169 is moved to allow spring s to drop through opening 169a, the spring s' is retained in block 166.

As shown in Fig. 30, spring 174 is confined between a shoulder 180 of rod 175 and an arm 181 of bar 170 (to which plate 169 is attached), the smaller portion 182 of said rod 175 passing through a hole in arm 181 and being attached by a pin 183 to a retaining collar 184. Spring s gravitates into the lamp socket as shown in Fig. 18.

The next operation performed by the machine is to assemble a non-conducting bushing b upon the spring s as shown in Fig. 19. The bushings b are contained in a second vibratory bowl feeder 190 supported upon bars 161. The function of this feeder is to cause the bushings b to move into the upper end of a chute 191 (Fig. 3) which provides a groove 192 (Fig. 25) which receives the flange of the bushing, the bushing portion of smaller diameter being received in the space between plates 193 attached to the chute 191. The feeder 190 causes the bushings to move upwardly on an inclined plate 194 (Fig. 3) and then to enter the chute 191 with the flange of each bushing received by groove 192. Therefore the shank of the bushing extends to the right (Fig. 3) and then extends downwardly at the lower end of the chute (Fig. 22). As shown in Fig. 22, the lowermost bushing b moves, by the pressure of bushings further up in the chute, against

a plate 194 of a bracket 195 supported by plate 196 attached to mounting pad 197 welded to the tube 45. Bracket 195 is secured to plate 196 in the desired position of adjustment by screws 198 passing through horizontal slots 199 of the bracket 195. By adjustment of plate 195, the lowermost bushing *b* is caused to align with a pilot pin 200 on the end of a bar 201 attached to a slide 202 (Fig. 25) and guided by a bracket 203 attached to plate 196. The slide 202 supports a roller 204 received by a cam groove 205 in a cam 206 driven by shaft 52. Rotation of shaft 52 causes movement of the pilot pin 200 and bar 201 from the position shown in Fig. 22 to that shown in Fig. 23. This movement takes place concurrently with a movement of chute 191 from the position shown in Fig. 3 and Fig. 22 to the position shown in Fig. 23. For this purpose, the chute 191 is provided with a support provided by pivot screw 210 (Fig. 3) supported by a bracket 211 attached to the feeder 190. Screw 210 provides a bearing for a plate 212 attached to the chute 191. A spring 213 connected to the bracket 211 and the chute 191 urges the chute clockwise so that a roller 214 supported by a lug 215 attached to the chute is urged against a cam 217 supported by cam 206 and retained in desired position thereon by a ring 218 which screws 219 attach to cam 206. The timing between cams 206 and 217 is such to cause the pilot 200 to be received by the hole in the bushing *b* which is against the plate 194 as the lower end of the chute 191 begins moving toward the position shown in Fig. 23 so that the lower end of the chute will clear the lower end of bar 201. Concurrently with this movement, the bushing *b* next to be discharged is caused to be retained upon the chute by a lever 220 pivoted on a pin 221 supported by ears 222 attached to the chute and urged counterclockwise by a spring 223 connecting the lever with the chute, said movement being permitted as a stop portion 224 of lever 220 moves away from a stop plate 225 attached to the bracket 203. Thus the lowermost bushing *b* in the chute is caused to gravitate into assembly with the spring *s* as shown in Fig. 19, while the next bushing *b*' is retained upon the chute.

The stations of the dial 100 are indicated by radial dot-dash lines marked, respectively, I (the lamp socket loading station), II (for the spring assembly station), III (for the bushing assembling station), IV (for the wire assembly station) and V (for the ejecting station).

While a workholder at station I is receiving a lamp socket, a lamp socket at station II is receiving a spring, a bushing *b* is being assembled at station III, the parts in a workholder at station IV are under a funnel-like guide comprised of half shell members 230, one of which is shown in Fig. 20. These members, when brought together, provide a guide for the insertion of the conductor conducting an insulating wire *w*, the core wire of which has been attached to a contact button *c*. When together, the members 230 receive a wire *w*, moved downwardly by an operator, and guide the lower end of the wire into the bushing *b*. When the members 230 are separated, the wire gravitates into the position shown in Fig. 20 with the contact *c* supported by the bushing.

As shown in Fig. 2, the upper end of shaft 57 extends through the inner race of a ball bearing 231, the outer race of which is retained by a bracket 232 which, as shown in Fig. 1, is attached to the horizontal portion 233 of a rod 234 which

extends vertically from a ring 235 attached to plate 40. Shaft 57 drives a cam 237 (Fig. 36) which cooperates with a roller 238 pivotally supported by rod 239 guided by a bore 240 of a plate 241 attached to bracket 232. The roller 238 is urged against cam 237 by a spring 242. A smaller rod 243 attached to rod 239 extends through a tube 244 and has a threaded portion 245 receiving a nut 246, the tightening of which secures the tube 244 to the rod 239. Tube 244 provides rack teeth 247 engaging a gear segment 248 journaled on a stud 249 supported by bracket 232 and retained by a resilient wire snap ring 249a received by groove 250 of the stud 249. Gear segment 248 meshes with a gear segment 251 journaled in the same manner as gear segment 248. The two gear segments 248 and 251 have arms, each of which support a member 230. After indexing is completed the members 230 are moved together to provide a guide for the wire *w*. Before indexing begins the members 230 are separated so that the wire is free to gravitate through the bushing to the position shown in Fig. 20.

After the assembly is complete, it is caused to be ejected from the dial 100 by movement of the lamp socket LS to the position shown in dot-dash lines in Fig. 21. For this purpose, there is associated with each workholder an ejector bar 260 (Figs. 2 and 35). Bar 260 is received by part 102a of notch 102 and is attached to a rod 261 which, as shown in Fig. 2, has a portion of larger diameter guided by a block 262 attached to the dial and carrying a roller 263 engageable with a fixed cam 264 attached to tube 48 in the desired position of adjustment by set screw 265. A spring 266 surrounding the smaller portion of the rod 261 and confined between the larger portion thereof and the right end of block 262 urges the roller 263 into engagement with the cam 264. Whenever a workholder arrives at ejection station V, a high lobe of the cam receives the roller 263 and effects the right movement of the bar 260 which presses upon the flange *f* of the lamp socket LS to eject the assembly.

While the embodiment of the present invention as herein disclosed, constitutes a preferred form, it is to be understood that other forms might be adopted.

What is claimed is as follows:

1. Apparatus for automatically assembling a metal socket, a helical spring within the socket and a non-conducting bushing upon the spring and for guiding a conductor wire adapted to be inserted through the bushing after assembly in the socket, said apparatus comprising a conveyor, a plurality of socket receiving work-holders in said conveyor, each of which is moved by the conveyor successively into a plurality of assembling stations, namely, a socket assembling station, a spring assembling station and a bushing assembling station, means effecting movement of a socket to a position adjacent the conveyor, means operating to move a socket laterally into a work holder from its position adjacent the conveyor when the work holder is positioned at the socket assembling station, means effecting movement of a spring to a position in axial alignment with a socket when the latter is positioned at the spring assembling station, means effecting movement of a spring axially into the socket from its position in alignment with said socket, means effecting movement of a bushing to a position in axial alignment with a socket when said socket is at the bushing assembling

station and means operating to move said bushing into the socket after the spring has been assembled therein in order to position the bushing so that it extends into said spring, wire guiding means and means intermittently moving the conveyor to move the work-holders successively to the several assembling stations and means holding the conveyor stationary during the movement of the socket into a work-holder and during the assembling of a spring and bushing in the socket.

2. Apparatus for automatically assembling a metal socket, a helical spring within the socket and a non-conducting bushing upon the spring and for guiding a conductor wire adapted to be manually inserted through the bushing after assembly in the socket, said apparatus comprising a conveyor, a plurality of socket receiving work-holders in said conveyor, each of which is moved by the conveyor successively into a plurality of assembling stations, namely, a socket assembling station, a spring assembling station, a bushing assembling station and a wire assembling station, means effecting movement of a socket to a position adjacent the conveyor, means operating to move a socket laterally into a work-holder from its position adjacent the conveyor when the work-holder is positioned at the socket assembling station, means effecting movement of a spring to a position in axial alignment with a socket when the latter is positioned at the spring assembling station, means effecting movement of a spring axially into the socket from its position in alignment with said socket, means effecting movement of a bushing into a position in axial alignment with a socket when said socket is at the bushing assembling station and means operating to move said bushing axially into the socket after the spring has been assembled therein in order to position the bushing so that it extends into said spring, a wire guide at the wire assembling station comprising two members movable toward each other to form a wire guiding passage in axial alignment with a socket when the latter is moved to the wire assembling station and separable to permit the wire to be moved to the proper position in the socket, means automatically moving said members toward each other and separating them, means intermittently moving the conveyor so as to move the work-holders successively to the several assembling stations, means holding the conveyor stationary during the movement of the socket into the work-holder and during the assembling of the various parts within the socket.

3. Apparatus for automatically assembling a metal socket, a helical spring within the socket and a non-conducting bushing upon the spring and for guiding a conductor wire adapted to be manually inserted through the bushing after assembly in the socket, said apparatus comprising a conveyor, a plurality of socket receiving work-holders in said conveyor, each of which is moved by the conveyor successively into a plurality of assembling stations, namely, a socket assembling station, a spring assembling station, a bushing assembling station and a wire assembling station, means effecting movement of a socket to a position adjacent the conveyor, means operating to move a socket laterally into a work-holder from its position adjacent the conveyor when the work-holder is positioned at the socket assembling station, means effecting movement of a spring to a position in axial alignment with

a socket when the latter is positioned at the spring assembling station, means effecting movement of a spring axially into the socket from its position in alignment with said socket, means effecting movement of a bushing into a position in axial alignment with a socket when said socket is at the bushing assembling station and means operating to move said bushing axially into the socket after the spring has been assembled therein in order to position the bushing so that it extends into said spring, a wire guide at the wire assembling station comprising two members movable toward each other to form a wire guiding passage in axial alignment with a socket when the latter is moved to the wire assembling station and separable to permit the wire to be moved to the proper position in the socket, means automatically moving said members toward each other and separating them, means intermittently moving the conveyor so as to move the work-holders successively to the several assembling stations, means holding the conveyor stationary during the movement of the socket into the work-holder and during the assembling of the various parts within the socket, said means for moving the members of the wire guiding means toward and away from each other being operable while the conveyor is stationary.

4. Apparatus for automatically assembling a metal socket, a helical spring within the socket and a non-conducting bushing upon the spring and for guiding a conductor wire adapted to be manually inserted through the bushing after assembly in the socket, said apparatus comprising a conveyor, a plurality of socket receiving work-holders in said conveyor, each of which is moved by the conveyor successively into a plurality of assembling stations, namely, a socket assembling station, a spring assembling station, a bushing assembling station and a wire assembling station, each of said work-holders having a notch adapted to receive the socket, and means for yieldingly retaining the socket in said notch, means operating to move a socket laterally into a socket receiving notch, means moving the conveyor intermittently so as to bring the work-holders successively to the several assembling stations, apparatus at the spring and bushing assembling stations for moving a bushing and spring axially into a socket when the socket is positioned at the spring and bushing assembling stations, wire guiding means and means automatically operating said socket moving means and the means for moving the spring and bushing axially into said socket while the conveyor is stationary.

5. Apparatus for automatically assembling a metal socket, a helical spring within the socket and a non-conducting bushing upon the spring and for guiding a conductor wire adapted to be manually inserted through the bushing after assembly in the socket, said apparatus comprising a conveyor, a plurality of socket receiving work-holders in said conveyor, each of which is moved by the conveyor successively into a plurality of assembling stations, namely, a socket assembling station, a spring assembling station, a bushing assembling station and a wire assembling station, means effecting movement of a socket to a position adjacent the conveyor, means operating to move a socket laterally in one direction into a work-holder from its position adjacent the conveyor when the work-holder is positioned at the socket assembling station, means

effecting movement of a spring to a position in axial alignment with a socket when the latter is positioned at the spring assembling station, means effecting movement of a spring axially into the socket from its position in alignment with said socket, means effecting movement of a bushing into a position in axial alignment with a socket when said socket is at the bushing assembling station and means operating to move said bushing axially into the socket after the spring has been assembled therein in order to position the bushing so that it extends into said spring, a wire guide at the wire assembling station comprising two members movable toward each other to form a wire guiding passage in axial alignment with a socket when the latter is moved to the wire assembling station and separable to permit the wire to be moved to the proper position in the socket, means automatically operating to move said members toward each other and separating them, means intermittently moving the conveyor so as to move the work-holders successively to the several assembling stations, means holding the conveyor stationary during the movement of the socket into the work-holder and during the assembling of the various parts within the socket, said conveyor being also movable to carry the sockets to an unloading station, and means operable at the unloading station and while the conveyor is stationary for moving the socket laterally in the reverse direction to eject said socket and assembled parts from the conveyor.

6. Apparatus for automatically assembling a metal socket, a helical spring within the socket and a non-conducting bushing upon the spring and for guiding a conductor wire adapted to be manually inserted through the bushing after assembly in the socket, said apparatus comprising a conveyor, a plurality of socket receiving work-holders in said conveyor, each of which is moved

by the conveyor successively into a plurality of assembling stations, namely, a socket assembling stations, a spring assembling station, a bushing assembling station and a wire assembling station, each of said work-holders having a notch adapted to receive the socket, and means yieldingly retaining the socket in said notch, means operating to move a socket laterally in one direction into a socket receiving notch, means 10 moving the conveyor intermittently so as to bring the work-holders successively to the several assembling stations, apparatus at the spring and bushing assembling stations for moving a bushing and spring axially into a socket when the socket is positioned at the spring and bushing assembling stations, means operating said socket moving means and the means for moving the spring and bushing axially into said socket while the conveyor is stationary, said conveyor 15 being also movable to carry the sockets to an unloading station, wire guiding means and means operable at the unloading station and while the conveyor is stationary for moving the socket laterally in the reverse direction to eject said socket and assembled parts from the conveyor.
